V. ROYLE

OILER FOR HIGH SPEED ROUTERS

Filed Dec. 27, 1922

Inventor

Brookfield

UNITED STATES PATENT OFFICE.

VERNON ROYLE, OF PATERSON, NEW JERSEY.

OILER FOR HIGH-SPEED ROUTERS.

Application filed December 27, 1922. Serial No. 609,291.

This invention relates to oil cups, and particularly to a cup for distributing oil in a predetermined quantity to a spindle running at high speed, and has for an object 5 to provide the cup with a measure for predetermined the quantity of lubricant supplied to the cup, and with means for preventing the supply of lubricant to the cup except through said measure.

10 It is intended to be applied to oil cups shown, described and claimed in United States Letters Patent No. 776,262, dated November 29, 1904, and United States Letters Patent No. 784,280, dated March 7, 15 1905, with an object in view of providing a cup comprising a casing having a plug secured thereto for protecting the body of absorbent material in the casing, which plug is provided with an opening and a measure 20 depending therefrom and in communication with the bottom of the casing.

Another object is to provide a cup having a plug with an opening therethrough, and provided with a spring actuated cover for 25 automatically closing the opening.

A practical embodiment of my invention is represented in the accompanying drawing, in which

Fig. 1 represents a side elevation of my 30 improved oil cup as it appears when applied to a routing cutter.

Fig. 2 represents a longitudinal section taken in the plane of the line II—II of Fig. 1.

Fig. 3 represents a horizontal section 35 taken in the plane of the line III—III of Fig. 1.

Fig. 4 represents a plan view of the plug, cover, and measure, on an enlarged scale.

40 Fig. 5 represents a vertical section taken in the plane of the line V—V of Fig. 4.

Fig. 6 represents a vertical section taken in the plane of the line VI—VI of Fig. 4, and

45 Fig. 7 represents a vertical central section of the casing of the oil cup.

It is to be understood that the parts which support the spindle bearing and spindle form in themselves no part of my present 50 invention, except so far as they form a suitable support for the oil cup which I have chosen to illustrate my invention, and which is adapted to feed oil to the spindle of a routing machine.

55 The said spindle is denoted by 1, the box

in which it rotates by 2, and the bearing which supports the box by 3.

The casing of the oil cup is denoted by 4, and is here shown as cylindrical in form and adapted to be held clasped to the bearing 3 60 by means of spring arm 5 which may be swung into and out of engagement with the casing 4 to lock and release it.

A plug 6 is inserted within the casing 4 and provided with a peripheral flange 7 65 which rests upon the upper edge of the casing. This plug has an opening 8 therethrough, in which a tube 9 is fitted to depend therefrom. A cover 10 is pivotally secured to the plug 6 by means of a screw 11 having 70 a threaded engagement with the plug.

The cover 10 has an inlet 12 which is arranged to be moved into and out of register with the tube 9. This cover is normally held with its inlet 12 out of register 75 with the tube 9 by means of a spring 13 housed in a recess 14 in the plug 6, one end of which spring is secured at 15 in the plug, and the other end at 16 in the cover. The inlet 12 in the cover 10 is manually brought 80 into register with the tube 9 by means of a lug 17 extending beyond the periphery of the cover. The plug is secured in position in the casing by means of a screw 18, which screw is arranged in position to be engaged 85 by the lug 17 when the inlet 12 and tube 9 are in alinement.

A body of absorbing material 19 is preferably made to fit and substantially fill the interior of the casing 4, with the exception 90 of a groove or perforation 20 extending longitudinally of the body, in the present instance, at one side of the body, and preferably at the side farthest from the outlet 21 through which the oil is conducted from the absorbing material 19 to the spindle 1. The perforation or groove 20 is intended 95 to receive the tube 9 which is in communication at its bottom with the body of absorbing material within the casing 4.

The capacity of the tube 9 is predetermined, and the tube is made of such dimension as to hold the quantity of lubricant which is found to be most satisfactory for lubricating the spindle for a predetermined 105 length of time during its operation.

For example, if it be found that one drop of lubricant will be sufficient to lubricate the spindle for a period of ten hours' run and it be desired to replenish the supply after 110

each day's run, then the measure 9 would have a capacity of one drop and all that would be required to replenish the oil cup would be to quickly fill the measure 9 before an opportunity is given for the oil to be absorbed by the absorbent body. The charge of oil as soon as the cup is closed will be gradually picked up by the body of absorbent materials within the cup and will be gradually transmitted to the spindle by means of a wick 22 of absorbent material which is intended to pass from contact with the spindle 1 through the tubular outlet 21 and through a perforation 23, extending transversely through the body of absorbent material 19.

By the arrangement of the plug and cover on the casing, it is evident that the oil admitted to the absorbent material must pass through the tube 9 and to the bottom of the casing, thereby preventing an operator from carelessly supplying lubricant to the top of the absorbent material where it will be immediately carried off by the wick to the spindle and which would result in an inadequate supply from the run. It is highly desirable that the supply of lubricant be passed through the measure to the bottom of the casing so that it will be caused to flow upwardly and thoroughly saturate the absorbent material before it passes through the wick to the spindle.

It is evident that various changes may be resorted to in the form, construction and arrangement of the several parts without departing from the spirit and scope of my invention; hence, I do not intend to be limited to the specific details herein shown and described, except as they may be included in the claims.

What I claim is:

1. The combination with an oil cup comprising, a casing, a body of absorbent material fitted within the casing, and a wick of absorbent material leading from the body of absorbent material through the casing, of a plug inserted in and secured to the casing for protecting the absorbent material, said

plug having a measure depending therefrom for the reception of a charge of lubricant of predetermined quantity, and a cover provided with an inlet arranged to be moved into register with said measure in the plug, said cover normally closing the measure.

2. The combination with an oil cup comprising, a casing, a body of absorbent material fitted within the casing, and a wick of absorbent material leading from the body of absorbent material through the casing, of a plug inserted in and secured to the casing for protecting the absorbent material, said plug having a measure depending therefrom for the reception of a charge of lubricant of predetermined quantity, and a spring actuated cover provided with an inlet arranged to be moved into register with said measure in the plug, said cover normally closing the measure.

3. The combination with an oil cup comprising, a casing, a body of absorbent material fitted within the casing, and a wick of absorbent material leading from the body of absorbent material through the casing, of a plug inserted in and secured to the casing for protecting the absorbent material, said plug having a tubular measure depending therefrom for determining the amount of an oil charge, and a cover movable to normally close said measure.

4. The combination with an oil cup comprising, a casing, a body of absorbent material fitted within the casing, and a wick of absorbent material leading from the body of absorbent material through the casing, of a plug inserted in and secured to the casing for protecting the absorbent material, said plug having a tubular measure depending therefrom for determining the amount of an oil charge, said measure being embedded in the body of absorbent material, and a spring actuated cover movable to normally close the measure.

In testimony, that I claim the foregoing as my invention, I have signed my name this 18th day of December, 1922.

VERNON ROYLE.
